CLAIM

The ornamental design for headset with boom microphone, substantially as shown and described.

DESCRIPTION

FIG. 1 is a front and right side perspective view of a headset with boom microphone showing our new design, a headset with boom microphone where the boom microphone is connected to the left side housing is a mirror image; FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

FIGS. 1-7 show a headset with a boom microphone connected to the right-side housing.

The dotted line portions of the drawings represent environmental structure only and do not form part of the claimed design.
